A. ALBRECHT

INSULATOR SUPPORT

Filed Dec. 26, 1922

FIG. 1

FIG. 2

FIG. 3

FIG. 4

INVENTOR
ARTHUR ALBRECHT
BY Edward E. Longan
ATTY.

UNITED STATES PATENT OFFICE.

ARTHUR ALBRECHT, OF ST. LOUIS, MISSOURI, ASSIGNEE OF ONE-HALF TO JASPER BLACKBURN, OF WEBSTER GROVES, MISSOURI.

INSULATOR SUPPORT.

Application filed December 26, 1922. Serial No. 608,875.

To all whom it may concern:

Be it known that I, ARTHUR ALBRECHT, a citizen of the United States, and resident of the city of St. Louis and State of Missouri, have invented certain new and useful Improvements in Insulator Supports, of which the following is a specification containing a full, clear, and exact description, reference being had to the accompanying drawings, forming a part thereof.

My invention relates to improvements in insulator supports and has for its primary object an insulator support which can be secured in a brick or stone wall without employing wooden plugs, expansion bolts or similar fastening means.

A further object is to construct an insulator support which is held within a brick or stone wall by friction and to which various types of porcelain or glass insulators can be attached, and one which can also be used as a cable support.

In the drawings:

Fig. 1 is a perspective view of my device; Fig. 2 is a side elevation of the same showing it in position within a brick wall and with one type of insulator attached thereto;

Fig. 3 is a top plan view of a modified form of support and

Fig. 4 is a side elevation of the same showing it in position in a brick wall.

In the construction of my device I employ a body of resilient metal 5, this body which is preferably of flat material has its one end 6 bent at right angles to the main body forming a head, the portion 6 is provided with an opening 7 which is to permit the insertion of a bolt for securing the insulator thereto, in the body 5 and near the portion 6 is a second opening 8 which is also for the purpose of attaching an insulator, this is clearly shown in Fig. 2. The end of the body 5 opposite the upward portion 6 is slotted forming a plurality of tongues 9, 10 and 11, these tongues have their ends 12 terminating in substantially the same horizontal plane, but their intermediate portions are alternately bent upward and downward as at 13 so as to occupy more space than the thickness of the material from which the support is made. In Figs. 3 and 4 I have shown a form of support which consists of a body portion 14, its forward end terminating in a cylindrical portion 15,

this cylindrical portion is provided with a screw threaded portion 16 which extends at right angles to the cylindrical portion and with a boss 17 which is for driving purposes, the rear end of the plate 14 is provided with tongues 18, 19 and 20 which are constructed similar to the tongues 9, 10 and 11, adjacent the forward end of the body portion 14 are tongues 21, these tongues are for the purpose of preventing a plate from tipping or rocking after it has been inserted in the wall. 22 and 23 represent adjacent bricks and 24 the mortar or cement between them.

In securing my device to a brick or stone wall, the mortar between two adjacent bricks or stones is dug out to a predetermined depth depending entirely on the distance that an insulator is to be from the wall, the ends 12 of the tongues 9, 10 and 11 are then inserted in the opening thus made, a hammer is now brought into action and the device driven in, the bent portions normally 13 occupying more room than the space between the bricks causes the tongues to assume the position shown in Figs. 2 and 4, and to bind tightly against the bricks and hold the support in position.

With the device shown in Figs. 1 and 2 the spool insulators 25 are preferably used but if it is desired to support a cable, the end 6 is turned in the position indicated by dotted lines in Fig. 2 and the cable laid on the body portion 5, it may then be secured by passing a wire through the openings 7 and 8 which will prevent the cable from becoming detached therefrom.

The insertion of the device illustrated in Figs. 3 and 4 is identically the same but in this instance the tongues 21 furnish an additional support near the forward end of the plate or body and prevents it from tilting.

I may also employ the tongues 21 on the device shown in Figs. 1 and 2 without departing from the spirit of my invention.

My device is held in the wall by means of friction set up by the tongues when the device is driven in position, of course, it is not desirable to remove any more mortar or cement from between the bricks or stones than is required to take care of the width of the support as otherwise lateral swinging might take place. While I have shown my device inserted in the horizontal joints of a wall,

2
still it is obvious that the same may be inserted between the joints that are either vertical, or in any other position without departing from the spirit of my invention.

5 Having fully described my invention, what I claim is:—

1. An insulator support comprising a flat body portion formed of spring metal and provided on one of its ends with a portion 10 extending at an angle to the body portion, a tongue carried by each edge of the body portion, and an intermediate tongue carried by the body portion, the said first mentioned tongues and the intermediate tongues being 15 bent in opposite directions so as to occupy more space than the thickness of the body portion.
2. An insulator support comprising a body portion formed of flat spring metal 20 provided at the rear end with tongues formed integral therewith, tongues formed on the body portion between the first mentioned tongues and the opposite end of said body portion, all of said tongues provided 25 with bent portions so as to occupy more space than the thickness of the body portion, and means for securing an electrical conductor to the front end of the body portion.
3. An insulator support comprising a body portion of flat resilient material 30 provided at one end with an insulator attaching means, and adjacent its other end with a plurality of bent portions, a plurality of bent portions intermediate the ends, all of

said bent portions so arranged as to normally occupy a greater vertical space than the thickness of the material, whereby said support is frictionally held in position without the use of extraneous fastening means. 35

4. An insulator support comprising a flat 40 body portion of resilient material provided at one end with a plurality of integrally formed tongues so bent as to occupy more space than the thickness of the material, the other end of said body portion provided 45 with an insulator attaching means arranged at an angle to the body portion, and a plurality of tongues intermediate the ends of said body portion, said tongues arranged to normally occupy more space than the thickness 50 of the body portion and adapted to be compressed when the support is placed in position, all of said tongues adapted to hold the device in position without the use of extraneous fastening means. 55

5. A device of the class described comprising a flat body portion of spring material having one end bent at an angle thereto thereby forming a head, an integral tongue formed on said body portion, said tongue 60 having its free end extending toward the head and normally spaced apart from the body portion, and electrical conductor supporting means carried by said head.

In testimony whereof, I have signed my 65 name to this specification.

ARTHUR ALBRECHT.
